Primary Examiner — Karen Kearney*Assistant Examiner* — Katherine Holbrow(74) *Attorney, Agent, or Firm* — Cantor Colburn LLP(57) **CLAIM**

We claim, the ornamental design for a display screen or portion thereof with graphical user interface, as shown and described.

DESCRIPTION

The sole FIGURE is a front view of a display screen or portion thereof with graphical user interface showing our new design.

The broken line showing of the display screen or portion thereof and graphical user interface are included for the purpose of illustrating environmental structure and portions of the article and form no part of the claimed design.
